DICE CUP

Michael Liberson, Chicago, Ill.

Application February 7, 1940, Serial No. 317,707

2 Claims. (Cl. 273—145)

My invention contemplates and provides a dice cup for use in playing various games of amusement, which is so constructed as to prevent unfair manipulation of the dice.

Some dice game players become adept, even expert, in defeating the natural odds of play by palming dice and predetermining their throw. For example, when such a player picks up the dice from the playing board, one of the dice is segregated from the other dice and palmed in the hand with which the dice cup is shaken. A die is chosen which has its numbered face down which the player wishes the die to present when it is thrown. The hand with which the dice cup is shaken, and in which the segregated die is palmed, is generally placed over the mouth of the dice cup. The palmed die is then held by this hand against the inside rim of the cup and is not shaken with the other dice. When the dice are thrown, the palmed die is expertly rolled or laid on the playing board, turning through 180 degrees from the position it had when held against the rim of the cup.

Another method of predetermining the throw of dice is generally even more difficult to detect than the first mentioned method. In such latter method, the dice are picked up from the playing board with both hands and one of the dice is segregated in the hand with which the player shakes the dice cup. The player palms a die which has the numbered face down which the player desires to throw. After the player has shaken the dice, the dice cup is transferred to the other hand for the throw. As the transfer takes place, the segregated die is slipped along the outside of the dice cup to the bottom thereof and held thereagainst by the hand with which the throw is made. As the throw is made, the segregated or palmed die is laid on the playing surface with the numbered face showing that the player has predetermined.

A salient feature and advantage of the present invention resides in the provision of annular ridges running around the outside periphery of the dice cup for preventing a player from slipping a die along the outside of the dice cup from the top to the bottom thereof.

Another important feature and advantage of the present invention resides in the provision of ridges along the upper rim and bottom edge of the cup for preventing manipulation of the dice at these locations.

Another important feature and advantage of the present invention resides in the provision of diagonally extending ribs on the inside of the

5 dice cup to prevent a player from holding a die against the inside rim of the cup as the dice are being thrown and to insure that the dice are rolled or tumbled as they are ejected from the box.

Another important feature and advantage of the present invention is the provision of a dice cup constructed of plastic material such as rubber or the like which is stiffened around the 10 upper rim of the cup without adding substantially to the thickness thereof.

Still another feature and advantage of the present invention is the provision of a dice cup embodying the objects described which is simple in construction, economical to manufacture and which may be held in a player's hand without inconvenience.

Other features, objects and advantages of the present invention will appear from the following detailed description, having reference to the accompanying sheet of drawings, wherein:

Fig. 1 is a side elevational view of the dice cup of my invention;

Fig. 2 is a top plan view of the dice cup shown 25 in Fig. 1;

Fig. 3 is a vertical sectional view of the dice cup of my invention; and

Fig. 4 is a horizontal sectional view taken in the plane of the line 4—4 of Fig. 3 and looking 30 in the direction indicated by the arrows.

Similar characters of reference refer to similar parts throughout the several views.

In the drawing, 10 indicates the body of the dice cup of my invention, such body being preferably made of moulded rubber or other preferably flexible, plastic composition. The cup may, of course, be constructed of leather or the like. Around the upper rim of the cup extends the annular metal supporting ring 11 which has its upper and lower edges bent around the moulded annular shoulder 12 of the dice cup body 10. The metal supporting ring 11 is adapted to strengthen the upper end of the flexible cup to prevent it from being squeezed out of its normal cylindrical shape without adding materially to the weight or mass of the cup. Spaced from the annular supporting ring 11 and the annular base flange 13 are a plurality of annular ridges 14 extending around the outside of the body 10. Two such ridges 14 are shown in the preferred construction illustrated in the figures, but it is understood, of course, that a greater or lesser number of such ridges may be used if desired. The annular base flange 13 and the annular ridges 14 are preferably integral with the body

of the cup 10 when such cup is made of moulded rubber or other plastic composition. Such ridges 14 and flange 13 may be separately secured to the body 10 of the dice cup when such body is made of leather or the like.

The ridges 14 are preferably of semicircular cross section, the radius of such circle being approximately $\frac{1}{8}$ ". The size of these ridges may, of course, be varied provided they are sufficiently large so as to obstruct the passage of a die moved along the outside surface of the cup, and provided they are small enough so as not to interfere with the convenient handling of the cup.

Extending diagonally upward on the inside of the cup from the bottom thereof (somewhat as shown in Markens Patent No. 1,103,366) is a plurality of ridges 15, each of the ridges 15 being spaced approximately $\frac{1}{8}$ of an inch from each other. It is important, however, that near the upper portion of the inside of the cup these diagonally extending ridges 15 change their direction and extend diagonally toward the rim of the cup in a direction at an angle of approximately 90 degrees more or less to that in which they extended in the lower portion of the cup.

If the ridges 15 continued in the same direction to the rim, an adept player could support a die in the space between two ridges, or, if the ridges were close together, a die could be supported on two adjacent ridges. In the drawing it will be noted that the terminus 16 of each ridge at the lip of the cup is on a vertical line spaced from the corner 17 where the next ridge 15 changes its direction. Hence at no place at the lip of the cup is it feasible to support a die to accomplish an inside palming as described previously herein.

The ridges 15 are preferably slightly smaller than the ridges 14. They need only be sufficiently large to insure tumbling of the dice as the dice are ejected from the cup, and sufficiently large so as to provide projections breaking the surface on the inner rim of the cup to prevent palming thereagainst.

The upper and lower flanges or shoulders 12 and 13 and the annular ridges 14 on the outside of the cup will effectively prevent a player from palming a die on the outside of the cup. In the event that a player should attempt to so palm a

die when using my dice cup, such palming will be readily apparent and easy to detect because the ridges 14 and flanges 12 and 13 break up the outer surface of the cup, leaving no surface on which the palming can covertly be effected.

Similarly, the diagonal ridges 15 on the inside of the rim of the cup will prevent a player from palming a die on such inside rim. The diagonal ridges which are below the upper ridges just described and which extend at an angle to such upper ridges will insure that the dice are rolled or tumbled as they are ejected from the cup.

The spaced annular ridges 14, as well as the annular base flange 13 and shoulder 12, which function to break the exterior surface of the cup, may take slightly different forms than the preferred embodiment illustrated in the drawing. For example, knob or button-like projections of sufficient size could be used to break the exterior surface of the cup to prevent outside palming. Similarly, diagonally extending ridges somewhat as shown on the inside of the cup could be utilized to break the exterior surface of the cup. I prefer, however, the embodiment shown.

Having thus illustrated and described a preferred form of my invention, I wish to avail myself of all equivalent embodiments as defined by the appended claims.

What I desire to secure by Letters Patent of the United States is:

1. A dice cup for games having a substantially cylindrical body, an outwardly projecting annular flange along the upper rim of the cup, and a plurality of relatively large annular ridges about the body of the cup between said flange and the bottom of the cup, said ridges projecting outwardly from the body of the cup substantially as far as the annular flange.

2. A dice cup for games having a substantially cylindrical body, a plurality of spaced ridges on the inside of the cup running diagonally upward in one direction, said ridges changing direction near the lip of the cup and extending diagonally to the lip in a direction approximately at right angles to the direction of the lower portion of the ridges.

MICHAEL LIBERSON.
